UNITED STATES PATENT OFFICE

ALBERT WEISS, OF BASSERSDORF, CT. ZURICH, SWITZERLAND, ASSIGNOR TO THE FIRM OF SWISS MASCHINE-TOOL WORKS, OERLIKON, OF OERLIKON, SWITZERLAND.

LATHE-BED CONSTRUCTION.

1,406,789.

Specification of Letters Patent. Patented Feb. 14, 1922.

Application filed March 31, 1921. Serial No. 457,489.

To all whom it may concern:

Be it known that I, ALBERT WEISS, a citizen of the Republic of Switzerland, residing at Bassersdorf, Ct. Zurich, Switzerland, have invented certain new and useful Improvements in Lathe-Bed Construction, (for which applications have been filed in Switzerland February 13, 1914; in Germany May 23, 1914; in France December 29, 1914; in 10 Italy March 31, 1915; in Austria December 15, 1917; in Great Britain February 25, 1915; in Belgium February 22, 1915, and in Russia March 13, 1915;) and I do hereby declare the following to be a full, clear, and 15 exact description of the invention, such as will enable others skilled in the art to which it appertains to make and use the same, reference being had to the accompanying drawings, and to letters or figures of reference marked thereon, which form a part 20 of this specification.

In the working of a slide-rest lathe of the ordinary type, or a capstan or turret lathe, the accuracy of the operation, the life of the 25 mechanism, and the quality of the output depend primarily on the accuracy with which the slide is guided, and the permanency of the guides.

My invention provides an improved arrangement of the guides and the mechanism actuating the slides, whereby an exceptional length of the bearing surfaces is obtained, and the invention consists in a combination wherein the rack is fixed to the bed above 30 the main guide of the slide rest, covering the same, and the lead screw is arranged directly below the said main guide, and is thus protected by the same.

This arrangement affords the advantage 40 of great rigidity when the work requires the application of considerable power, involving strain on the bed, and if the latter bed has a gap, as is frequently the case for various classes of work, the placing of the 45 screw below the main guide makes it possible to run the slide over the gap, if necessary, without effecting any change in the actuating gear, or providing an indirect drive therefor.

50 The invention is illustrated in the accompanying drawings, showing one form of construction.

Figure 1 is a partial cross section taken through the bed and slide rest at the gap.

Figure 2 is a cross-section taken through 55 the bed and rack.

Figure 3 is a front view showing the gap.

Figure 4 is a front view of the slide rest.

Figure 5 is a cross-section of part of the bed and the guard at the gap. 60

Figure 6 is a front view of part of the carriage with the apron or front plate of the gear box on the slide removed.

Figure 7 is a plan view of the carriage.

In the drawings 1 designates the bed, having at the top guides 2 and 3 for the sliding carriage. The guides 4 and 5 for the slide 6 (4 being the main guide) are at the sides of the bed, lower down. To prevent bending of the saddle of the slide 6, the same 70 has an additional guide surface resting on the guide 2. To prevent the rising and lateral deviation of the slide under stress during the working the same is provided with flanges 8, 9 which engage under the parts 5 75 and 11 of the bed, and can be tightened up by means of screws, to compensate for wear and regulate the pressure of the slide on the bed. In order to give the slide long bearing surfaces, it is provided with extensions 19 80 fore and aft of the gear box 7, engaging over the angular or prismatic main guide 4.

The rack 12 is screwed to the bed above the guide 4, at one side of the bed and exposed at the top, but the rack is made wide 85 so that it protects the guide from shavings. For this purpose the rack may be made in two parts.

The lead screw 13 and the control shaft 14 are below the bed, protected by the laterally projecting guide member 11 already referred to. The pinion 15 is mounted on the slide between the guide 4 and the channel provided for the rack. 90

In order to also protect the guide 4 at 95 the gap of the bed, a guard 16 is provided at this part, and conforms to the shape of the slide, so that the slide can be moved uninterruptedly to the head stock. In Figures 1 and 4, 17 designates the contact surface between the body of the slide and the bottom of the gear box, these parts having at the sides lugs 18, which are screwed to each other. The position of the joint at this part obviates torque in the cutting screws, 100 as the joint is close to the nut 19 and there is practically no leverage.

The projections 11 of the bed, with the

flanges 8, 9, secure a proper proportion of length and width of bearing surfaces, and afford support, during the working of the lathe, which effectively prevent deviation 5 and jamming and ensures smooth running of the slide.

I claim—

1. In a lathe bed construction, a prismatic guide at the side of the bed, a rack 10 supported on the bed above the guide and protecting said guide from chips, and a lead screw below the guide and protected thereby.

2. In a lathe bed construction, front and

rear guides, a rack arranged over and protecting the front guide, a feed-screw below said guide, a slide on said guides, flanges on said slide engaging beneath the guides, and lateral extensions on said slide engaging the front guide.

3. In a lathe bed construction, front and rear guides, a rack having a gap secured above and protecting one of the guides from chips and a guard for said gap.

In testimony that I claim the foregoing 25 as my invention, I have signed my name.

ALBERT WEISS.
